Arthur C. De Vorn, Cleveland, Ohio, assignor to National Ring & Leather Corporation, Mansfield, Ohio, a corporation of Michigan

Application October 7, 1949, Serial No. 5,349

Term of patent 7 years

(Cl. D80—9)

To all whom it may concern:

Be it known that I, Arthur C. De Vorn, a citizen of the United States and a resident of Cleveland, in the County of Cuyahoga and State of Ohio, have invented a new, original, and ornamental Design for a Merchandise Display Device, of which the following is a specification, reference being had to the accompanying drawings, forming a part hereof.

In said drawings, Fig. 1 is a front perspective view of a merchandise display device showing my new design; Fig. 2 is a rear perspective view; Fig. 3 is a rear perspective view showing the rear closure in an open position; and Fig. 4 is a side elevational view thereof.

I claim:

The ornamental design for a merchandise display device, as shown.

ARTHUR C. DE VORN.
